DOMINIQUE PETRIN, OF MONTAGUE CITY, MASSACHUSETTS

LOCKING PLATE FOR FISH RODS

Application filed September 18, 1929. Serial No. 393,549.

This invention relates to improved attachment means for the reel base of a fishing rod on its seat.

The object of the invention is to provide attachment means for fastening the reel base to the corresponding seat portion of the rod which is of simple, durable and inexpensive construction, at the same time of perfectly reliable function as to fixing the relative position of the two members, and of the greatest convenience in assembling or disassembling the parts. Another object is to form the attachment means in such a manner that the reel base can be made symmetrical and be placed on the rod seat with one and the same end either pointing to the front or to the rear end of the rod.

How these various ends and still other advantages have been obtained, will appear from the subsequent description of the invention in connection with the drawings, both of which exemplify the design preferred at the present time.

Fig. 1 is a side elevation of the assembled and tightly locked equipment with some parts shown in section and with the reel proper broken away;

Fig. 2 is a transverse section on line 2—2 of Fig. 1;

Fig. 3 is a transverse section on line 3—3 of Fig. 1;

Fig. 4 is a transverse section on line 4—4 of Fig. 1;

Fig. 5 is a schematic picture on enlarged scale of the ring position when in free shoving condition;

Fig. 6 is an imaginary picture of the ring in tightly locking or clamping condition; and

Fig. 7 is a similar picture of the ring in an intermediate position.

Referring now to the drawings, Figs. 1 to 4 more particularly, it will be noted that my arrangement consists of three parts which are a tubular seat member 1 which forms part of the fish rod adjacent the handle thereof; a reel base 10 which is usually an integral part of the reel proper not shown in the figure, and a ring 20 of unsymmetrically oblong or

substantially oval form which is free to slide along its axis.

This ring is made from resilient material such as steel and by virtue of its oval shape it consists of portions of greater or lesser eccentricity with respect to the axis of the tubular seat member. By holding the ring about the seat tube with its more eccentric portions uppermost, the ring opening will permit the ring to be slid over the assembled base plate and seat member so that it may assume a position on the axis of the tube as shown in Fig. 1. Its radial position may then be changed until it assumes the relation represented in Figs. 1 and 4 with the eccentric portion depending. In this position, as will appear later on, the ring tightly locks the reel and the seat together in fixed position with respect to each other. The disassembling of the parts is effected by going through the reverse order of ring movements.

The seat tube is near one of its ends provided with a flat pocket formed by a patch 3 of metal sheet soldered or, in some other suitable way, joined to the outer surface of the tube and extending over a segment of the tube circumference. A slot 4 in the patch extends for some distance parallel with and near the opening margin of the pocket.

The reel base plate which is shorter in length than the seat tube has a bearing face, the contour of which fits the curvature of the tube and laterally covers a segment of somewhat smaller width than the pocket. Each end of the base plate terminates in a similar upstanding flange portion 11 which portions are preferably struck up from the base plate. The upstanding broken away studs 12 belong to the connecting portions between the reel proper, not shown in the figure, and the reel base plate.

In order to assemble the base plate 10 or the reel respectively on the seat tube 1, the plate is held axially aligned, but to a certain degree inclined with respect to the tube and then with its inclined end inserted in the pocket and gradually swung down into contiguous relation with the tube, whereby the slot 4 and the inserted flange 11 will engage as a hook and eye. Since the lateral exten-

sion of the flange snugly fits the width of the slot, this end of the base plate is securely held against any peripheral movements and, besides, the whole plate is fixed against any axial displacement.

It is manifest that with this construction it is immaterial which of the two end flanges is selected for introduction in the pocket since the reel proper is mounted on a perfectly symmetrical base plate. This reversibility is a very valuable feature of my construction. Reels are sometimes used in upright position on the rod, sometimes in depending position, and left and right handed persons require a different positioning of the reels for obtaining the correct winding sense for the line. All such various requirements can be met by a symmetric reel construction according to this invention by simply inserting the base plate with proper heed to the desired winding sense.

After the hook and eye engagement has been made in the simple manner described before, all that remains to be done for completely fixing the position of the reel plate is to shove the ring 20 over the other end flange 11 and then to turn it by 180 degrees. These manipulations of the ring are facilitated by a rolled up or bead portion 21 of the ring.

The functioning of the ring as locking means will be best explained by referring to the schematic illustrations Figs. 5 to 7.

The ring as mentioned already is of some highly resilient material such as steel and may, therefore, be temporarily deformed or deflected when being turned about a solid contour not in conformity to its interior outline or opening. In all of the Figures 5 to 7, the ring is shown in its normal or non-deflected condition. Fig. 5 shows the relative position of the various elements while the ring is ready to be shoved over the flange 11 of the base plate. This flange is indicated in broken lines and shows how there is just sufficient play for the ring to be slipped over the flange. Fig. 6 is a picture illustrating how the cross sectional area of the undeflected ring in its tightly locking relation corresponding to a 180 degree turn from its initial position, would cut into the cross section of the seat tube between the points *a* and *b* on each side of the tube. Fig. 7 is a similar picture of the ring when turned by 45 degrees out of its locking position of Fig. 6 and is, therefore, characteristic of the intermediate ring positions while passing from shoving to locking position or conversely. The cut-in portions are in such intermediate positions unsymmetrical and in the case of Fig. 7 distributed between the intersections *c*, *d* and *e*, *f*, respectively. It will also be noted from this figure that the cutting or overlapping areas in total are much larger in this case than they were in the locking position. This

amounts to saying that the ring, while being turned from its shoving to its locking position, passes through a series of elastic states which start with zero deflection, reach a maximum deflection and then drop again to a certain locking deflection as given by Fig. 6. Since these conditions are determined by the relative position of the ring and the base plate, it follows that in the locking position these two members are in a definite and stable relation with respect to each other, and that any forces trying to change this position are checked from doing so by elastic forces of deformation set up in the assembling. It has been found from actual constructions that these forces provide ample safety against any normal tendencies to dislocate the non-pocketed end of the base plate on the rod, and this fact is further explained if one considers that any relative rotation between the ring and base plate encounters a wedging resistance in the interspaces marked by *w* in Fig. 6 between the ring and the seat tube. On the other and, the eccentric portion 22 of the ring offers a convenient thumb rest and turning lever for moving the ring about its axis so that the normal effort of a person suffices to turn the ring in and out of its locking position.

After having described my invention in a detailed manner, I wish to point out some further advantages besides those already mentioned as compared to former constructions.

All cooperating elements of this assembling are of most simple shapes, and each of them can be inexpensively formed in pressing or stamping machines. The tubular seat body, for instance, can be manufactured in one and the same machine job since it need not have any depressions or ridges as former structures required.

The absence of all precision machine work such as tapering, screw-threaded or toothed elements does not only simplify and cheapen the manufacture but renders this assembling much more reliable in service. Fishing rods and their requisites are frequently exposed to adverse conditions such as corrosive water, fine abrasive dust, sand drift, etc., all of which are enemies of delicate mechanical parts and, in due course of time, will detract from their accurate functioning and give rise to much trouble. It is evident that my simple and rugged design is free from all such deficiencies.

Various minor changes may, of course, be made without departing from the spirit of the invention, and in this regard I do not mean to be limited by the exemplified structure but, rather, by the claims.

What I claim is:

1. In combination with a fishing rod, a tubular reel seat having near one of its ends and partly extending over its circumference

- a pocket slotted along and near its open edge, a seat-conforming reel base plate with identical pocket-insertable and slot-fitting end portions for insertion of either of them
- 5 in the pocket with hook-and-eye engagement in its slot, and a resilient ring slidable on said tubular seat of substantially oval form so as to allow, when turned in shoving position, to be shoved without deflection over
- 10 the non-pocketed end of the assembled base plate and, when thereupon turned in opposite locking position, to tightly clamp the seat and base plate within its deflected contour.
- 15 2. The combination in a fishing rod of a seat member, a reel base plate provided with a terminal flange, and a resilient ring having an oval cross-sectional form, and shaped so that in one position of rotation it may be
- 20 slid over the terminal flange of the base plate and in another position of rotation it will grip both the seat member and the base plate symmetrically by its own resilience.
3. The combination in a fishing rod of a
- 25 seat member of arcuate cross-section, a reel base plate of circular cross section and provided with a terminal flange, and a resilient ring having a symmetrical enlargement at one side sufficient to permit it to be passed
- 30 over the terminal flange of the base plate when in one position of rotation, said ring having an internal contour causing a four point gripping contact on the seat member and base plate when the ring is rotated half
- 35 a revolution from the first named position.

In testimony whereof I have affixed my signature.

DOMINIQUE PETRIN.
